Filed Nov. 14, 1966, Ser. No. 593,864
10 Claims. (Cl. 238—315)

ABSTRACT OF THE DISCLOSURE

A railway tie anchor having wall portions upstanding from a base, each of said wall portions having at least one slot identical to a slot in the other, each slot intersecting the upper edge of the wall and extending toward the base at an angle therewith, the slot conforming generally to the contour of the rail flange portion to be gripped, with the vertical height of the anchor being such that when installed on a rail a portion thereof extends into abutting relationship with a rail supporting cross tie to anchor the tie longitudinal of the rail.

This invention relates generally to anchors for railroad ties and more specifically to a new and improved anchor which fixes railroad ties longitudinal of the rail in a more positive and simple manner than heretofore possible.

Railway tie anchors have been widely used in the prior art for the purposes of fixing ties longitudinally of the rail to prevent movement thereof under the cyclical loading imposed by traffic over the rails. The problem of maintaining ties fixed with respect to the longitudinal direction of the rail has been increased in recent years in that heavier loads, heavier power units and faster speeds have caused greater problems with track expansion. These loads cause track movement which in turn, if the ties are not anchored to the track, cause progressive movement of the ties to the point where the ties "stack up" at certain points leaving large gaps between ties. If this condition is not corrected, track failure ultimately results because of improper support thereof. The anchors, fixed to the lower face of the rail, engage the ties or tie plates so that movement of the ties is resisted.

Many prior art anchors are configured and disposed on the rail in such a manner as to abut against the tie plate which supports the rail. The tie plate is connected to each tie by conventional spikes driven therethrough into the tie. A primary disadvantage of this type of anchor is that the strain, imposed through longitudinal movement of the rail or forces tending to move the tie longitudinally on the rail, is directed through the anchor against the tie plate thereby tending to loosen the spikes holding the plate and rail eventually resulting in a loose plate and consequently a loose rail. Such anchors are illustrated by the Spencer Patent No. 2,522,314 and the Liebenthal Patent No. 3,019,988. The above-mentioned problem is solved to a certain degree by anchors which include a depending segment extending in such a manner to abut the transverse face of an adjacent tie thereby imposing stresses directly on the tie itself and avoiding loosening of the plate. These prior art devices, however, are formed from bar stock, the formation of which is expensive and not subject to mass production techniques as is required in articles of this type. Such prior art anchors are typified by the patents to Gillmor No. 1,292,756 and Payne No. 2,936,127.

Another problem, inherent in prior art anchors, is that the size of the rail is different for curved and straight track so that, heretofore, two types of anchors had to be stored and supplied in order to meet the requirements of track laying crews. This duplication in supply is expensive and oftentimes results in mix ups and delays in track laying where the wrong type of anchor is furnished.

2

It is an object of this invention to provide a new and improved rail tie anchor which avoids the disadvantages of prior art tie anchors.

It is another object of this invention to provide a rail tie anchor which may be interchangeably used on curved and straight rail by providing a compatible dual slot configuration in the anchor formed to receive rails of different size.

It is a further object of this invention to provide a tie anchor which can be mass produced simply and inexpensively by furnishing a structure which is formed from plate material.

It is still another object of this invention to provide a rail tie anchor formed from plate material which is flexible for easy installation and yet of sufficient depth to contact the rail tie directly and thereby avoid stress on the tie plate and spike system by providing a rail anchor having an angled orientation when installed on a track.

It is still a further object of this invention to furnish a tie anchor having dual rail size capability by providing a structure having angled rail-receiving slots therein.

Other objects and many of the attendant advantages of this invention will be better understood by those skilled in the art by reference to the following detailed description when viewed in light of the accompanying figures wherein like parts throughout the figures thereof are indicated by like numerals and wherein:

FIGURE 1 is a sectional elevational view of an anchor in accordance with the invention taken along the lines 30 1—1 of FIGURE 2;

FIGURE 2 is a side elevational view of FIGURE 1;

FIGURE 3 is a front elevational view of the anchor of FIGURE 1 installed on a rail; and

FIGURE 4 is a side elevational view of the installed anchor of FIGURE 3.

Referring now to FIGURES 1 and 2 for a more detailed description, an anchor 10 is formed from steel plate bent into a U-shaped configuration (FIGURE 2), comprising a base portion 12 and upstanding walls 14 and 14', terminating in upper surfaces 16 and 16'. A first slot, shown generally at 18 and defined on the lower edge thereof by a side surface 19, intersects the upper edges 16 and 16' of the side portions 14 and 14' and extends at an angle toward the base portion 12. The lower end of the slot 18 defines upper and lower jaws 20 and 22 respectively for gripping the flange of a railroad rail as will be described in more detail below. The upper jaw 20 has formed thereon a flange grip surface 24 and an expansion surface 26, the surface 26 being of a smaller angle with respect to the side surface 19 than the grip surface 24. The lower end of the slot terminates in a slot bottom surface 28 with stress relieving cutouts 30 formed in the corners defined by the intersection of surfaces 19 and 26 therewith. The upper end of the slot 18 is provided with a slot top surface 52 disposed perpendicular to the side surface to form a lug 34, the purpose of which will be described below.

A second slot shown generally at 36, disposed to intersect the upper surfaces 16 and 16' of the side portion 14 and 14', is formed in the anchor 10 at an angle substantially opposite to that of and intersecting the first slot 18. The lower edge of the second slot 36 is defined by a side surface 38, the lower end thereof defining upper and lower jaws 40 and 42 respectively. The upper jaw 40 has formed thereon a flange grip surface 44 and an expansion surface 46 angularly related to one another in a similar fashion to the flange grip and expansion surfaces 20 and 24 of the slot 18. The slot 36 is also provided with a slot bottom surface 48 and stress relieving cutouts 50 at the intersection thereof with surfaces 42 and 46. The upper end of the slot 36 is provided with a slot top surface 52 which is disposed perpendicular to the side surface 38 to

form a second lug 54 thereon. The second slot 36 serves to provide a material cutout, reducing the cross sectional area of both the jaw 20 and the material supporting the lug 34 to a degree sufficient to provide the desired resiliency for the anchor so that it is better adapted for the purposes for which it is to be used.

The slot 36 also provides a rail gripping structure of different dimensions than those of the slot 18 so that the anchor may be used interchangeably on rails of different size. For example, 115 lb. rail is normally used for straight track and 132 lb. rail is normally used for curved track. Heretofore, it has been necessary to stock and supply two different-sized anchors so that the curved track, as well as straight track, can be anchored. By providing the dual capability of the anchor of this invention, the duplication and possible mix up inherent in the anchors of the prior art is avoided. The slots also complement one another by providing a means to achieve the necessary resilience as described above. In order to identify the proper slot for use with a particular rail, a cutout 56 is provided in the base portion 12 to indicate the required slot, for example, for the curved rail. In the event that the slot 36 is used to grip a rail, then slot 18 will serve a material-reducing means for the jaw 40 and lug 54.

Referring now to FIGURE 3 of the drawings, the anchor 10 is shown installed on a conventional rail 58. The rail is provided with base flanges 60 and 62 which form a lower rail surface 64 and sloping upper flange surfaces 66 and 68 respectively. The rail is supported on a conventional tie plate 70 which, in turn, is mounted on a tie 72 and is connected thereto by spikes 73. The flanges 60 and 62 terminate at their outer surfaces with vertically disposed flange faces 74 and 76 respectively. As can be best seen by reference to FIGURE 4 the anchor 10 is mounted on the rail 58 so that the wall 14' thereof abuts the transverse vertical surface of the tie 72 to provide an anchor therefor.

Assuming that the rail 58 is a straight rail, the anchor is installed as follows: The anchor is fitted on the rail flange so that the flange 60 enters the slot 18 as far as can be accomplished by hand. In this condition, the geometry of the jaws 20 and 22 and the lug 34 is such that an interference will occur primarily between the flange gripping surface 24 and the upper flange surface 66 and between the lug 34 and the lower rail surface 64 precluding further movement of the anchor by hand. At this point, the anchor is struck, on the end portion at the point indicated by the arrow in FIGURE 3, with suitable force to wedge the flange gripping surface 24 on the upper jaw 20 and the side surface 19 on the lower jaw 22 onto the flange 60 to provide suitable gripping thereof. When the anchor has moved transversely of the rail to a certain degree, the lug 34 will pass the flange face 76 and will snap up into the position shown in FIGURE 3 thereby locking the anchor 10 to the rail 58. The surfaces 19, 24 and 26 embed themselves into the rail 58 to provide required holding power for the anchor without causing structural damage to the flange 60. In this condition, the anchor will not move longitudinally of the rail and, by installing the anchor on either side of and in abutment with the transverse surface of the ties 72, the ties are longitudinally fixed with respect to the rails. The slot bottom 28 prevents overdriving of the anchor and thereby breakage thereof and the cutouts 30 provide stress relief means to prevent stress concentration at the corners of the bottom of the slot 18.

Due to the slope or angle disposition of the slot 18 with respect to the base portion 12, the anchor is, in an installed position, at an angle with respect to the lower surface of the rail 58 and the tie 72 so that a large portion of the surface area of the wall 14' extends into abutting engagement with the transverse surface of the tie 72. This arrangement provides a first benefit in that a suitable area of contact between the anchor 10 and the tie 72 is thereby provided without imposing too large a cross sectional area in the flexing portions of the anchor, i.e., the section be-

neath the lug 34 and the cross sectional area of the upper jaw 20. If the slot 18 were to be in parallel relationship with the lower surface of the base portion 12 as is common in prior art anchors, the resulting depth, to extend the anchor beneath the rail to the transverse surface of the tie 72, would result in an extremely large cross-sectional area in the material beneath the lug 34 thereby rendering the anchor unnecessarily rigid and difficult, if not impossible to install.

By providing direct contact with the tie 72, strain due to forces tending to shift the tie longitudinally with respect to the rail are not placed on the tie plate 20 or the spikes 73 thereby avoiding loosening thereof with the attendant disadvantages set forth above. The angled orientation of the slots in the anchor also allows the compatible inclusion of two slots which would be impossible if the slots were substantially parallel to the base of the anchor.

The structure of the anchor is also such that, in the event of a derailment, the upper jaw 20 will fracture thereby preventing damage to the flange 60.

What has been set forth above has been intended to be exemplary of an embodiment incorporating features in accordance with the invention to enable those skilled in the art in the understanding thereof. It should therefore be understood that, within the scope of the appended claims, the invention may be practiced other than as specifically described.

What is new and therefore desired to be protected by Letters Patent of the United States is:

1. A railway tie anchor comprising:

a base portion;
wall portions extending upwardly from said base portion;
at least one slot intersecting the upper edge of each of said wall portions in identical fashion and extending toward said base portion at an angle therewith, the lower end of said slot conforming generally to the contour of the lower surface flange face and upper surface of one flange of a rail, the lower end of said slot defining upper and lower jaws adapted to be driven transversely of a rail flange into gripping engagement with the upper and lower surfaces thereof, the upper end of said slot conforming generally to the lower surface and flange face of the other flange of a rail to define a locking lug for engaging that flange face;

the vertical height of said anchor being such that when installed on a rail a portion thereof extends into abutting relationship with a rail supporting cross tie to anchor said tie longitudinal of said rail.

2. An anchor in accordance with claim 1 wherein a relief slot is disposed in said wall portions beneath the upper end of said first-mentioned slot.

3. An anchor in accordance with claim 1 wherein one portion of said upper jaw is formed with a gripping surface of greater angle with respect to the surface of said lower jaw than the remaining portion thereof.

4. A railway tie anchor comprising:

a base portion,
upstanding wall portions on said base portion,
a first slot intersecting the upper edge of said wall portions and extending toward said base portion at an angle therewith, the lower end of said slot conforming generally to the contour of the lower surface flange face and upper surface of one flange of a rail, the lower end of said slot defining upper and lower jaws adapted to be driven transversely of a rail flange into gripping engagement with the upper and lower surfaces thereof, the upper end of said slot conforming generally to the lower surface and flange face of the other flange of a rail to define a locking lug for engaging that flange face,

a second slot similarly configured to said first slot disposed in said wall portions in an intersecting oppositely disposed direction to said first-mentioned slot.

5. An anchor in accordance with claim 4 wherein the vertical height of the anchor is such that when installed on a rail, a portion thereof extends into abutting relationship with a rail supporting cross tie to anchor said tie longitudinal of said rail.

6. An anchor in accordance with claim 4 wherein one portion of said upper jaw is formed with a gripping surface of greater angle with respect to the surface of said lower jaw than the remaining portion thereof.

7. An anchor in accordance with claim 4 wherein said second slot is formed to accommodate a rail of different dimensions than that accommodated by said first-mentioned slot.

8. An anchor in accordance with claim 7 wherein one portion of said upper jaw is formed with a gripping surface of greater angle with respect to the surface of said lower jaw than the remaining portion thereof.

9. An anchor in accordance with claim 7 wherein the corners of the lower ends of each of said slots are provided with stress-relieving cutouts.

10. An anchor in accordance with claim 9 wherein one portion of said upper jaw is formed with a gripping surface of greater angle with respect to the surface of said lower jaw than the remaining portion thereof.
